GUSTAV KEMMANN, OF BERLIN-GRÜNEWALD, GERMANY

RAILWAY SIGNALING SYSTEM

Application filed May 18, 1928, Serial No. 278,827, and in Germany May 20, 1927.

The invention relates to a signaling system which may be employed for steam or electric railways and especially in cases of very intense and quick traffic.

5 The essential feature consists therein, that a magnet arranged on the locomotive or other vehicle and a magnet arranged on the track are both provided with electric windings in such mutual relation as to produce by the inductive action arising from the passage of the one magnet near the other at once the necessary influences on the locomotive (braking, signaling on the driver's place) and on a relay operating the blocking devices on the 10 track. It is thereby possible to attain a special high security as the complete inter-dependency of the locomotive signals and the track blocking ensures that any trouble arising in the locomotive circuit will block the track and 15 any trouble arising in the track circuit will brake the locomotive or warn the driver.

In the drawings the until now known devices and the new device are shown in juxtaposition in diagrammatic views.

20 Fig. 1 shows a locomotive signaling magnet,

Fig. 2 shows a like magnet in coaction with a track magnet,

Fig. 3 shows a locomotive magnet in coaction with a track magnet for track blocking,

Fig. 4 shows a locomotive signaling magnet in coaction with a track magnet influenced by the position of the track signal,

Fig. 5 shows the new device, and

25 Figs. 5^a and 5^b illustrate modified forms of the structure disclosed in Fig. 5.

Figs. 6-9 illustrate more clearly the different functions of the new device.

According to Fig. 1, for exerting an inductive influence on the train, on the locomotive a magnet is arranged with windings and a source of electric current is so connected to said windings and the windings of a locomotive relay, that an alteration of the magnetic field of said magnet exerts an influence on said relay. Fig. 2 shows the same device arranged above a track magnet which may be a permanent magnet or only an iron part and serves for closing and augmenting the magnetic field of the locomotive magnet so as to

induce in the windings of the latter an electric voltage which in the windings of the closed relay produces an opposite current so as to open the relay and effect the several influences as for instance a signaling action for the driver, a train braking action and the like.

According to Fig. 3 an inverse operation is effected in so far, as on the locomotive a simple magnet or iron core is arranged, and on the track a magnet with windings, a relay and a current source are similarly arranged as previously on the locomotive. In this arrangement the opening of the relay, caused by the approach of the locomotive, produces the several track blocking operations. Apparently for this device current exciting the track magnets must be continuously generated.

According to Fig. 4, in a device corresponding to Figs. 1 and 2 the track magnet is provided with a winding connected to contacts of the track signal in such way that in the clear position of the signal the circuit of said winding is closed, whereas in danger position of the signal the circuit of said winding is interrupted. In this case the locomotive magnet passing the track magnet induces a voltage in the windings of the latter, and if the signal is at clear and its contacts are closed, said voltage produces a current which produces a magnetic field opposed to the field of the locomotive magnet. Hereby the augmentation of the field of the locomotive magnet is essentially compensated and the current induced by said field augmentation becomes not strong enough for causing the relay to open. Therefore the relay remains closed and no influence is exerted on the train. In the opposite event, if the track signal is at danger and its contacts are open, current cannot flow in the circuit of the track element and the influence is exerted on the train as described in connection with Figs. 1 and 2.

According to Figs. 5 and 6 the invention consists in providing on the locomotive a device as described in connection with Figs. 1, 2 and 4, whereas, on the track, devices similar to those shown in Figs. 3 and 4 are provided, and further arrangements are provided for effecting the track blocking in dependence on the locomotive currents. For this

purpose the windings of the track magnet are closed through the track signal contacts and a blocking relay, which governs all operations necessary for the automatic blocking.

5 In Fig. 5 on the locomotive the current source is shown as a generator for making clear that it is not necessary to use direct current, but with special advantage it is possible to use alternating current and to measure the 10 capacities and inductances, if necessary by inserting condensers and additional coils (see Figs. 5^a and 5^b), in such a way that the oscillations in the track circuits correspond to those generated in the locomotive circuits, 15 whereby the effectiveness is greatly enlarged, and sure action is attained with only small current generation. The invention further is practicable with directly acting currents as well as with currents normally flowing continuously and interrupted for effecting the 20 operations.

In Figs. 6 to 9, the invention is illustrated in a normal danger system, but it is also applicable for a normal safety system. The 25 reference numerals 10, 11 and 12 indicate the several block signals, and 13, 14 and 15 the corresponding track magnets depending on the signal contacts 16, 17 and 18 respectively. The track relays in the circuits of said track 30 magnets are shown at 19, 20 and 21. They are adhering relays which by having a weak constant magnetic field, which does not suffice for attracting the armature, but suffices for holding it after being closed when 35 closed remain so as long as no current (induced by a locomotive magnet) passes through their coils. Small restoring solenoid magnets 22, 23 and 24 are provided which, when traversed by current, return the armatures of the 40 said track relays 19, 20 and 21 into their normal position, so as to close the contacts 25, 26 and 27 of the track relays 19, 20 and 21, which serve for operating special block 45 relays 28, 29, 30 having, for instance, five contacts each for governing the several blocking operations, namely 34 and 37 (35 and 38, 36 and 39) for governing the restoring magnets 22, 23, 24; 40 and 46 (41 and 47, 42 and 48) for governing the relays 28, 29, 30; and 50 43 (44, 45) for governing the motors of the signals 10, 11, 12.

In all the illustrations the train is indicated by a locomotive magnet 1.

Figs. 6 to 9 are diagrams showing the several circuits which are operated by a train moving along the track from left to right. As shown in the drawing, when the relays 28, 29, 30 are excited by a current, the contacts 43, 44, 45 and 46, 47, 48 are closed, the contacts 55 34, 35, 36 and 37, 38, 39 and 40, 41, 42 are open whereas in case these relays are not excited the contacts 43, 44, 45 and 46, 47, 48 are open, and 34, 35, 36 and 37, 38, 39 and 40, 41, 42 are closed. Various circuits serving 60 65 for initiating the operation and for switch-

ing in cases of disturbance are only diagrammatically shown as keys 49, 50.

Fig. 6, shows the track section 31, 32, 33 in free condition and a train 1 approaching section 31, the signal 10 having been moved into clear position by said train, and signal 12 having been moved into clear position by pressing the key 50, for instance, with the purpose of giving passage to a locomotive having no locomotive magnet. 75

Fig. 7 shows the condition produced by the train at the moment of passing said signal. In consequence of the magnetic impulse the relay 19 becomes deenergized and its contact 25 becomes interrupted, so that the relay 28 becomes deenergized and opens its contact 43 which serves for operating the signal 10, as shown diagrammatically in Figs. 6 and 7, so that said signal falls into danger position and secures the passed train. At the same time the relay 28 closes its contacts 34, 37, 40. Through the contact 40 a current flows to the relay 29, so that said latter relay attracts its core or plate, whereby its contacts 35, 38, 41 are opened, and 44, 47 are closed so as to move the signal 11 into the clear position, and by closing its contact 17 signal 11 makes its train stop inoperative. 80

Fig. 8 shows the effect of the passage of the train 1 beyond the signal 11; as described in connection with Fig. 7, the relay 20 becomes deenergized; the contacts 35, 38, 41 of relay 29 are closed, and 44, 47 are interrupted. Thereby the signal 11 comes into danger position. Through the contacts 41, 27 the relay 30 on the signal 12 becomes excited so as to close its contact 45 which causes the latter signal to go into clear position. Through the contacts 38, 34 the restoring magnet 22 is energized so as to close contact 25 and prepare the signal 10 to go into clear position. 90

Fig. 9 shows the diagram with a train 1' entering track section 31 while the train 1 has just passed the section 32. The train 1' would be confronted by the signal 11 at danger as long as the train 1 had not passed the signal 12, for in this case the relay 30 would remain energized, but after the train 1 has passed the magnet 15 and deenergized the relay 30, the contact 39 is closed and through 100 this contact and contact 35 the contact 26 is closed so as to prepare the signal 11 to go into clear position. 110

As special advantages of the new arrangement the following may be mentioned. The automatic blocking is connected in the closest manner to the automatic train influencing without any remarkable special cost and complication. Accidents arising from block troubles or inattention of the locomotive 120 drivers or other employees are practically excluded, as each trouble arising in the block necessarily moves the appertaining signal into the closed position. A closed signal, even when not seen, necessarily causes the 125 130

train to be braked. Therefore utmost security is warranted.

Each train when passing the inlet signal of a block section protects itself rearwardly and at once moves the next forward signal into free position, if the next block section is free.

The costly apparatus, as inductance coils connected to the rails, extended insulating devices, and the expensive current consumption of the blocking by aid of rail currents are avoided. Only a simple additional implement is needed.

I claim:

- 15 1. A railway signaling system comprising in combination on the locomotive or other vehicle a magnet with windings, a relay connected to said windings and governing the train influencing devices, and on the track several so called track magnetizable cores with windings connected through a signaling switch to relays governing the blocking operations, said locomotive magnet and said track magnets being so arranged that when juxtaposed to each other by the running train the locomotive magnet influences the track magnet and is mutually influenced by the same track magnet according to the position of said signaling switch.
- 20 2. A railway signaling system as described in claim 1, wherein the windings of the track magnets are connected to the blocking relay through a signaling contact depending upon the position of the block signal.
- 25 3. A railway signaling system in combination on the locomotive or other vehicle a magnet with windings, an alternating current supply and a relay connected to said windings and current supply and governing the train influencing devices, and on the track several so called track magnetizable cores with windings connected to relays governing the blocking operations, said locomotive magnet and said track magnets being so arranged as to mutually influence themselves when juxtaposed to each other by the running train, and the current circuits of said track magnets having such capacity and inductance as to be in resonance with the frequency of the locomotive alternating currents.
- 30 4. A railway signaling system as described in claim 3, wherein to the blocking relay additional condensers or self induction coils are connected for producing resonance with the frequency of the locomotive alternating currents.

In witness whereof I affix my signature.
GUSTAV KEMMANN.
